US0D1071190S

(12) **United States Design Patent** (10) **Patent No.:** **US D1,071,190 S**
(45) **Date of Patent:** **** Apr. 15, 2025**

(54) **DISPOSABLE COVER**

- (71) Applicant: **Allen Medical Systems, Inc.**, Batesville, IN (US)
- (72) Inventors: **Michael M. Boucher**, Batesville, IN (US); **Hung D. Nguyen**, Batesville, IN (US); **Christopher Dubois**, Batesville, IN (US); **Andrew R. Marchand**, Batesville, IN (US); **Mary Kelly Chance**, Batesville, IN (US)
- (73) Assignee: **Allen Medical Systems, Inc.**, Batesville, IN (US)
- (**) Term: **15 Years**
- (21) Appl. No.: **29/876,868**
- (22) Filed: **May 30, 2023**
- (51) LOC (15) Cl. **24-02**
- (52) U.S. Cl. **USPC D24/128**
- (58) **Field of Classification Search**
USPC D24/127-130, 181, 199, 186, 132; D6/610-612
CPC .. B60R 7/043; B60N 2/60; A47D 5/00; A47D 5/006; A47D 7/002; A47D 15/003
See application file for complete search history.

(57) **CLAIM**

The ornamental design for a disposable cover as shown and described.

DESCRIPTION

FIG. 1 is a perspective view including the front, top and side of a disposable cover showing our new design;

FIG. 2 is a perspective view including the back, bottom and side of FIG. 1;

FIG. 3 is a perspective view including the top and side of FIGS. 1-2;

FIG. 4 is a perspective view including the bottom and opposite side of FIGS. 1-3;

FIG. 5 is a perspective view including the front, bottom and side of FIGS. 1-4;

FIG. 6 is a perspective view including the back, top and side of FIGS. 1-5;

FIG. 7 is a top plan view of FIGS. 1-6; and,

FIG. 8 is a bottom plan view of FIGS. 1-7.

1 Claim, 4 Drawing Sheets
